UNITED STATES PATENT OFFICE.

SYLVESTER J. SMALL, OF SEATTLE, WASHINGTON.

PRINTING-TELEGRAPH.

SPECIFICATION forming part of Letters Patent No. 621,863, dated March 28, 1899.

Application filed November 13, 1897. Serial No. 658,417. (No model.)

To all whom it may concern:

Be it known that I, SYLVESTER J. SMALL, a citizen of the United States, residing at Seattle, in the county of King and State of Washington, have invented a certain new and useful Improvement in Printing-Telegraphs, of which the following is a specification, reference being had to the accompanying drawings.

10 This improvement relates to that class of printing-telegraphs in which the printing is done on a type-writer; and the object of it is to provide an apparatus of this class that will be convenient to operate, rapid and sure in 15 operation, and not likely to get out of order.

To these ends the invention consists in the peculiar construction, arrangement, and combinations of parts hereinafter more particularly described and then definitely claimed at 20 the end hereof.

In the accompanying drawings, Figure 1 is a side elevation of the receiver or mechanism for operating the type-writer, the latter being represented by a single type-lever and its accompanying parts. Fig. 2 is an end elevation of the same. Fig. 3 is a plan view thereof. Fig. 4 is a plan of part of a cutting apparatus, partly in section. Fig. 5, Sheet 1, is a perspective view of a support for the cutter 30 thereof. Fig. 6 is a front view of a cutting apparatus, partly in section, on the line xx in Fig. 7. Fig. 7 represents a cross-section on the line yy in Fig. 6. Fig. 8 is a detail of part of a guide, with a belt and pulley, in dotted lines. Fig. 9 is a perspective view of a holding and pushing device with its operating magnets removed. Fig. 10 is a detail of a part of the same on an enlarged scale. Fig. 11 is a perspective view of part of a switch-board, showing the mode of completing the circuits for operating the type-writer. Fig. 12 is a detail of a modification thereof. Fig. 13 is a perspective view of the transmitting apparatus. Fig. 14 is a perspective detail of 45 a contact-plate in the same. Fig. 15 is a diagrammatic view showing the electric connections between the transmitter and the receiver and the local circuits for operating some of the parts of the receiver. Fig. 16 is 50 a diagrammatic plan of the circuits of the type-writing mechanism. Fig. 17 is an end elevation of a type-writing mechanism form-

ing a portion of the receiving apparatus, with parts represented as broken away and other parts left out to avoid confusion in the drawing. Fig. 18 is a similar view of the mechanism for operating the paper-cylinder. Fig. 19 is a detail of magnets used for changing the position of the cylinder in making capital letters. Fig. 20 is a plan of the paper-cylinder and its immediate connections. Fig. 21 is a central longitudinal section of the paper-cylinder. Fig. 22 is a cross-section of the same through the line zz in Fig. 21. Fig. 23 is a perspective detail of the bearing for the 65 paper-cylinder shaft. Figs. 24 and 25 are details of the paper-cylinder.

In the following description I shall refer to the details of the drawings by letters and numerals and will first describe the apparatus 70 for transmitting the message, next the receiving and operating apparatus, and lastly the details of the type-writing mechanism.

Referring now to Fig. 13, 1 represents a base having a raised part 2, of suitable non-conducting material, from which rises a binding-post 3, carrying a spring contact-arm 4, having a roller 5 on its lower end which makes contact, as hereinafter described, with a contact-plate 6, (shown in full in Fig. 14,) which 80 is provided with a binding-post 7 for the line-wire 8. At the forward end of the base is a pair of feeding-rolls 9, set in a suitable housing 9' and provided with a pulley 10, which may be driven by any suitable motor (not 85 shown) at a regulated speed, so as to feed through the contact-plate 6 a strip of perforated paper 11, which may be perforated by any suitable perforating-machine. (As no claim is made herein for such machine, it is 90 unnecessary to describe it.) The perforations, it will be seen, are at different distances apart, and it is the distance between them that indicates the different letters to be printed at the other end of the line. Suppose, for 95 instance, that all the letters of the alphabet are to be transmitted in succession. The first perforation would be one-sixteenth of an inch from the end of the slip, the second perforation, representing "B," would be one-eighth 100 of an inch from the first perforation, and the third perforation, representing "C," would be three-sixteenths of an inch from the previous perforation, and so on, the perforations rep-

resenting the letters each being one-sixteenth of an inch farther from the perforation next preceding it, if the entire alphabet were to be represented in this manner. It should be remembered, however, that the perforations do not really represent the letters, but the spaces between the perforations are the true representatives of the letters, as before stated. For convenience in illustration I have assumed that the spaces between the perforations increased regularly with the letters of the alphabet; but in practice I shall probably make the shorter spaces represent the letters mostly used—the vowels, for example—as it will save both time and material.

I will now describe the receiving and operating devices, in which 12 (see Figs. 1, 2, and 3) indicates a base supporting a casing 13, containing a motor or gearing of any convenient style, to which motion may be given by a pulley 14 on a shaft 15, connected with said gearing. On one of the shafts of said gearing is a brake-wheel 16, against which a brake 17 acts when a current passes through the electromagnets 18, so as to draw toward it an armature 19, held by a lever 20, which holds the brake 17 away from the wheel, as shown, when the current is not passing through the magnets 18, the lever itself being retracted by the spring 21, one end of which is attached to the lever and the other to an upright 22.

Mounted in suitable housings 23 are two feed-rollers 24, which are used to feed a strip of stiff paper 25 or other material through a suitable guide 26 (see Fig. 4) onto a small platform 27 under a holder 28, (see Fig. 9,) which is drawn down upon the strip of paper by magnets 29. (Not shown in Fig. 9, but illustrated in Figs. 1, 2, and 3.) These magnets act upon an armature 30, carried by a lever 31, one end of which carries the holder 28 and the other is threaded to receive an adjustable counterbalance 32, which reacts upon the lever 31 and lifts the holder when the magnets 29 are not energized.

Secured to the top of the casing is a cutter-carrier 33, (shown in detail at Fig. 5,) to which is pivoted at 34 a cutter 35, connected by a link 36 with a lever 37, to the outer end of which is connected a rod 38, carrying an armature 39, which is acted upon by the magnets 40, mounted on a support 41, overhanging the cutter 35, lever 37, &c. The armature is normally held above the magnets by springs 42, the lower ends of which are attached to the armature and their two upper ends to a yoke 43, which acts as a guide for the upper end of the rod 38. When the magnets 40 are energized, they attract the armature, which causes the rod 38 to descend and thus operate the cutter 35, which not only cuts off a piece of the strip, but bends the rear end of the cut-off piece, (indicated by the numeral 44, see Fig. 7,) and which I shall call a "letter-strip" in the further description of the operation of my invention.

Referring again to the lever 31, (see Fig. 9,)

it will be seen that it carries a forked pawl 45, having projections 46 (see Fig. 10) on the inner sides of both branches of the pawl, 70 which as the lever and pawl rise act upon the left side of two projections 47 on the lever 48, causing said lever to move toward the right, carrying with it a bent rod 49, pivoted in a fork 50 at the top of said lever 48. This 75 rod passes through a standard 51, which forms a guide for said rod and also for the lever 31, and carries at its forward end a pusher 52, which strikes the letter-strip 44 and pushes it down on the platform under a belt 53, passing over a roller 53' and operated by a pulley 54, (see Fig. 1,) driven by any suitable power. This belt carries the letter-strip down over an inclined switchboard 55, with the bent end of said letter-strip in a groove 56 in a bar 85 57, fixed at the side of the switchboard.

The switchboard 55 is provided with an insulating-strip 58, (see Figs. 1, 3, and 11,) in which are set contact-plates 59, attached to wires 60 and 61, one set of which, 60, is connected with a set of magnets 73 (see Figs. 1 and 17) for operating the type-bars of a type-writing mechanism, as hereinafter explained.

The switches 62 are connected to the switchboard by hinges 63, so as to swing upward, as indicated by the arrow in Fig. 11, and when so raised a contact-wire 64 will touch one of the contact-plates 59, as shown in said figure. Each switch has a lip 65 slightly projecting above the plane of the switchboard, and each lip is arranged slightly nearer the farther edge of the switchboard than the one immediately preceding it, as clearly shown in Fig. 3. As the switches are connected to the switchboard and the latter is connected to a 105 battery by the wire 55', all the switches on said board are of course in electrical connection with the battery.

In some cases instead of having the hinges at the top of the switches, as shown in Fig. 11, I may make them in the manner indicated by Fig. 12, in which the hinges are made in the edges of the plates, so as to be smooth on the top.

Referring now to the type-writing mechanism of my invention, which is represented by Fig. 17 of the drawings, 70 represents the frame of a type-writer provided with type-bars 71, hung in the frame in the usual manner and each carrying two characters 72, one being a lower-case letter, and the other a capital, a numeral, a punctuation-mark, or other character. At 73 are shown magnets which when energized draw down the armature 74 and by means of a link 75 operate the type-bar 71, so as to make it print in the usual manner.

Before describing the paper-cylinder and the means for operating the same I may premise that instead of printing the lines along the cylinder I print my lines around the cylinder, which necessitates peculiarities of construction which I will now describe.

Mounted in recesses in the top of the frame

are bearings 78, (see Figs. 17, 18, and 20,) carrying armatures 79, which are drawn in one direction by the magnets 80 and are carried away from the same when said magnets 5 are not energized by the springs 81. In these bearings 78 is mounted a shaft 82, carrying a block 83, forming a support for the paper-cylinder 84, Fig. 22, and which block is provided with antifriction-rollers 85 to enable 10 the cylinder to run easily over the block 83. At opposite ends of the said shaft 82 are arms 86, which carry a rod 87, that runs through one of the spaces in the block 83 and carries a spring 88, that bears against a forked 15 lug 89 on the inside of the paper-cylinder, the other end of the spring 88 bearing against one of the arms 86, and its office is to push the cylinder along as fast as an escapement 90 (see Figs. 21 and 22) will permit. This 20 escapement is pivotally mounted on a suitable hanger 91, secured in the block 83, and has at one end an armature 92, to be acted on by the magnets 93, while its other end is 25 acted on by a spring 94 in opposition to the magnets, the whole being so arranged that as the magnets are energized and operate the escapement the spring 88 feeds the cylinder lengthwise the necessary distance for another line of type-writing. The magnet 93 is 30 energized by means of a circuit c, whose wires run in opposite directions to revolving contact-rings 93' on shaft 82, which are in continual contact with fixed spring plates or 35 brushes 93", to which the remainder of the circuit is connected.

In writing a line the paper-cylinder is revolved by means of the mechanism herein-after described. Fast on the shaft 82 (see particularly Fig. 18) is a ratchet-wheel 95, 40 which is operated by a pawl 96, pivoted to a lever 97, mounted on the shaft 82 and having its outer end broadened out to act as an armature 98 to the magnet 99, and which is normally kept raised by the spiral spring 100. 45 At 101 in Figs. 18 and 20 is shown a wheel having a number of depressions or notches corresponding to the teeth on the wheel 95. In these notches rests a small roller or ball 102, attached to a spring-arm 103, mounted 50 upon the armature 79, the object of which device is to keep the cylinder steady in whatever position it may have been carried by the pawl 96.

The paper-cylinder may be made in different ways; but at present I prefer to make it in two parts hinged together, as shown at 120. The opposite sides of the cylinder are provided with flanges 121, one of which has pins 122, that enter holes in the other flange, so as 55 to firmly hold the edges of the paper (shown in dotted lines) between the flanges 121. The flanges fit in a groove 123 in the block 83, which forms a guide to prevent the rotation of the paper-cylinder around the block. The 60 edges of these flanges also form the teeth 124, with which the escapement 90 engages. On one half of the cylinder, near the hinges, is a

lug 125, which carries a spring-operated hinged clasp 126, having a notch 127, in which another lug 128 on the opposite half of the cylinder engages to keep the cylinder closed. 70 The free end of the clasp is turned downward, so as to engage with the side of the lug 128 and prevent the cylinder opening too wide. To insert the paper, the cylinder is opened, as 75 shown in Fig. 24, and placed on the paper and the edges of the latter folded over the flanges. The cylinder is then closed, and the lug 128 catches in the notch 127 in the clasp 126 and holds the flanges of the cylinder together, with 80 the edges of the paper held between them.

Fig. 19 shows a device for making and keeping closed the circuit of which the magnets 80 form a part until their work has been performed, when said circuit is broken in the 85 manner hereinafter described. This device consists of a magnet 104 and an armature 105, having an extension at right angles running through a guide 106 and carrying at its extremity an insulated contact-point, which 90 when the magnet 104 is energized, so as to attract its armature, is carried between the contact-plates 107, thus completing the electrical connection between the wires 108 of the circuit there indicated, which is part of the circuit for energizing the magnets 80. This device may be set in any convenient part of said circuit at will. To lessen the friction of the armature 105, antifriction-rollers are indicated by dotted lines in the guides 106. Normally 100 resting on the top of the armature 105 is a stop 109, attached to the armature 110 of the magnet 111, which is so arranged that when the armature 105 is attracted and is moved by the magnets 104 the stop 109 drops down behind 105 the armature 105 and holds it against the magnet 104, although the current may be cut off from said magnet. When it is desired that the armature 105 should be moved back, the magnet 111 is energized, which raises the armature 110 and the stop 109, which frees the armature 105, and it is then drawn back by the spring 112, the circuit of the magnet 104 having been broken as soon as the armature 105 had been drawn to said magnet. The different 110 electric circuits necessary to energize these magnets are shown in the diagrammatic views, Figs. 15 and 16. Referring first to Fig. 15, 113 represents the line-wire connected to the binding-post 3 of the transmitter, from 115 whence it passes to the magnet-coils 18 and thence to the ground at 114. The current in passing through said magnet-coils 18 attracts the armature 19 and its carrier 20, moving the contacts 115 and 117 against their companion 120 contacts 116 and 118, the contacts 117 and 118 being more particularly shown in Fig. 2. This movement of the contacts 115 and 117 completes the circuits for operating the paper-holding and paper-cutting mechanism 125 hereinbefore described. Referring now to the circuits shown in Fig. 16, which are designed to operate the type-writing mechanism, we find the switchboard 55, (shown in

full in Fig. 3,) to which are connected the circuits *a*, *b*, *c*, and *d*, the first of which is completed by the movement of the first switch of the switchboard, which energizes the magnets 104, which attract the armature 105 for making circuit *e* in order to shift the paper-cylinder by means of the magnets 80 for capitalizing. The second circuit *b* is completed by the second switch and energizes the magnet 111 to unlock the armature 105, thereby breaking the circuit *e* to allow the paper-cylinder to shift back for lower-case letters. The third circuit *c* is completed by the third switch, which energizes magnet 93 to operate the escapement 90 to allow the paper-cylinder to move longitudinally for printing a new line. The fourth circuit *d* is connected to each and all of the remaining switches of the switchboard by the wires 61, and the completion of the circuit *d* by the movement of any one of the switches (except the first three) energizes the magnet 99 to move the armature 98 in order to turn the paper-cylinder for printing another letter. It will of course be understood that each of the switches (except the first four) besides being connected with the common circuit *d* is connected to its own wire 60 for energizing its proper magnet 73 for operating the type-bar 71.

The above detailed description I believe is sufficient to give any person skilled in the art a full understanding of the operation of the different parts, and the following general description of the operation of the apparatus as a whole will be sufficient, in conjunction with said detailed description, to give a thorough knowledge of the invention and the way it is carried out.

The receiving operator having supplied the paper-cylinder with paper and the receiver with the continuous strip 25 and the message to be sent having been properly perforated in the strip 11, the sending operator causes the rollers to feed said perforated strip through the transmitter, and as soon as the end of the paper passes under the roll 5 contact is broken in the line-circuit, which demagnetizes the magnets 18, allowing the spring 21 to retract the lever 20 and draw the brake 17 away from the wheel 16, thus allowing the motor to move and cause the feed-rollers 24 to feed the strip 23 under the cutter 35. When a perforation in the strip 11 passes under the roller 5, contact is made with the plate 6 and the main line-circuit 113 is completed, which causes the magnets 18 to draw the armature 19 and lever 20 toward them and forces the brake 17 against the wheel 19, which thus stops the further motion of the motor and the cessation of feed of the strip 25. As soon as the contacts 115 and 117 touch the contacts 116 and 118 the local circuits *f* and *g* (see Fig. 15) are completed and the magnets 29 and 40 energized, which operate the holder and cutter, thereby cutting off and holding fast a letter-strip 44, which will be proportioned in length to the distance between the beginning of the

perforated paper strip and the first perforation therein, or between the two perforations where a perforation has previously passed under the roller 5. As soon as the perforation has passed from under the roller 5 the line-circuit is broken by the paper, thus demagnetizing the magnets 18, which allows the spring 21 to draw back the lever 20, and thus break the circuits *f* and *g*, allowing the counterbalance-weight 32 to operate the lever 31 and raise the holder 28 and pawl 45, carried by said lever, thus causing the projections 46 on the lower end of said pawl to operate the lever 48, which will give the pusher 52 a sudden thrust forward, carrying the letter-strip 44 down the platform 27, with its bent end under the belt 53, which is pressed down upon it by a guide-strip 130, which extends the whole length of the switchboard. This belt carries the letter-strip down over the switchboard a distance corresponding to its length, for as soon as it has been carried far enough down to touch and lift one of the lips 65 and the switch to which it is attached it descends beneath said switch and is carried down to the end of the groove 56, where it drops down out of the apparatus and is of no further use or effect. As the letter-strip 44 lifts the lip 65 it brings its contact-wire 64 into contact with its corresponding contact-plate 59, and thus completes either one of the circuits *a*, *b*, *c*, or *d*, according to which switch is raised by the letter-strip 44 as it passes down the switchboard, and at the same time that it completes circuit *d* it also completes the circuit of the magnet that operates the type-bar to print the desired letter on the paper on the paper-cylinder of the type-writer, except when said circuit is completed by raising the fourth switch, for that has no connection with a type-bar, it being simply used for spacing between words. When a word has been printed, a long strip that will lift the fourth switch from the top of the switchboard is cut off, and this will complete the circuit *d*, thus energizing the magnets 99 and turning the paper-cylinder sufficiently to make a space between the word just printed and the next one to be printed. If it is designed to print a capital or capitals, a strip is cut off, which will raise the first switch, thus completing the circuit *a* and moving the paper-cylinder laterally, where it is held by the locking-stop 109 until the desired capital or capitals have been printed by sending appropriate letter-strips through the switches below the fourth one from the top. When it is desired to again print small letters, a strip is cut off that will operate the second switch and complete the circuit *b*, thereby energizing the magnet 111 and unlocking the armature 105 and breaking the circuit *e*, allowing the spring 81 to draw the paper-cylinder back to its original position over the small letters on the type-bars. When a line has been completed and it is desired to move the cylinder longitudinally, a strip is cut off that will be of the

proper length to lift the third switch, which will complete the circuit *c*, thus operating the escapement 90, which will allow the spring 88 to push the paper-cylinder 84 along suffi-

ciently to make room for the printing of another line. From this it will be seen that after the message is properly prepared by perforating the strip 11 the sending of the message and the printing of the same are entirely automatic, as all that is necessary for the sender to do is to see that the rollers 9 properly feed through the perforated strip 11, and all that is necessary for the receiver to do is to see that the strip 25 is properly fed through and to supply the paper-cylinder with the necessary paper. To enable the latter to be conveniently done, the paper-cylinder is made in halves hinged together, as before explained, so that when the paper on it has been printed full the cylinder can be readily opened and removed, as it will then be at the left-hand end of the machine and nearly off the block 83; but before this is done a second cylinder, with the paper on it, is clasped over the right-hand end of the block 83 ready to take the place of the one about to be removed.

The perforation of the strip 11 may be made, as before mentioned, by any appropriate means; but I propose to use a machine of my own invention for the purpose, but as it is not claimed herein it is unnecessary to describe it. It should be understood, however, that such perforating means should be capable of making the perforations at varying distances apart to distinguish the characters to be printed and also to make perforations at such distances as to cut strips for operating the first four switches, which move without operating any of the type-bars.

I have referred to the use of paper for the letter-strips; but I do not limit myself to this material, as thin or soft metal or a compound of paper and metal may be used.

It is obvious that the mechanism employed by me may be varied to a considerable extent without departing from the spirit of my invention, and I do not wish to be understood as limiting myself to the precise forms of mechanisms used in carrying out the various functions of my apparatus.

It is also obvious that some of the parts of my invention may be used without using all the other parts described or shown.

While I have shown a series of magnets for operating some of the devices, it is obvious that a single magnet may be made of sufficient power to operate each part, and where in the following claims I use the word "magnet," I intend to be understood as covering the invention, whether one or more magnets are used in the combination.

What I claim as new is--

1. In an apparatus of the character described, the combination of a letter-strip cutter constructed to cut off strips of varying sizes, a series of switches, means for carrying the cut-off letter-strips to the switches,

electric type-writing mechanism, and circuits from the switches to the electric devices for operating the type-bars, substantially as described.

2. In an apparatus of the character described, the combination of a letter-strip cutter constructed to cut off strips of varying sizes, a multiple switchboard, means for carrying the cut-off letter-strips varying distances along the switchboard, an electric type-writing mechanism, and circuits from the switches of the multiple switchboard to the magnets for operating the type-bars of said type-writing mechanism, substantially as described.

3. In a device of the character described, the combination of a letter-strip cutter constructed to cut off strips of varying sizes, a multiple switchboard having a series of rising-and-falling switches, means for carrying the cut-off letter-strips over and through the switches, an electric type-writing mechanism, and circuits from said switches to the magnets of said type-writing mechanism, substantially as described.

4. In an apparatus of the character described, the combination of a letter-strip cutter constructed to cut off strips of varying sizes, a multiple switchboard, means for carrying the cut-off letter-strips to the switches, type-bars operated by magnets, circuits from the switches to the magnets of said type-bars, and a circuit for operating a spacing device between different words printed on the type-bars, substantially as described.

5. In an apparatus of the character described, the combination of a letter-strip cutter constructed to cut off strips of varying sizes, a multiple switchboard, means for carrying the cut-off letter-strips to the switches of said board, an electrically-operated type-writer, circuits from said switches to the type-bar magnets of said type-writer, a circuit and mechanism for operating a spacing device, and mechanism for automatically changing the position of the paper to print a new line, substantially as described.

6. In an apparatus of the character described, the combination of a letter-strip cutter constructed to cut off strips of varying sizes, a multiple switchboard, means for carrying the cut-off letter-strips to the switches of said board, an electromagnetically-operated type-writer, circuits from the switches to the magnets of said type-writer, a circuit and mechanism for operating a spacing device between the words printed by said type-writer, and means for moving the paper-cylinder for capitalization, substantially as described.

7. In an apparatus of the character described, the combination of a letter-strip cutter constructed to cut off strips of varying sizes, a multiple switchboard, means for carrying the cut-off letter-strips to the switches of said board, an electromagnetically-operated type-writer, circuits from the switches to the magnets of said type-writer, means for

automatically operating a spacing device, a circuit and means for moving the paper-cylinder for capitalization, and a locking device for holding said paper-cylinder in the capitalizing position, substantially as described.

8. In an apparatus of the character described, the combination of a letter-strip cutter constructed to cut off strips of varying sizes, a multiple switchboard, means for carrying the cut-off letter-strips to the switches of said board, an electromagnetically-operated type-writer, circuits from the switches to the magnets of the type-writer, means for operating a spacing device, a circuit and means for moving the paper-cylinder laterally, a locking device for locking the same, and a circuit and means for unlocking the same, substantially as described.

9. In an apparatus of the character described, the combination of a letter-strip cutter constructed to cut off strips of varying sizes, a multiple switchboard, a letter-strip carrier, an electric type-writer, circuits from the switches of said board to the type-writer, a circuit and means for operating a spacing device, and circuits and means for rotating the paper-cylinder and moving the same laterally and longitudinally, substantially as described.

10. In a printing-telegraph, the combination with a transmitter, of a letter-strip cutter constructed to cut off strips of varying sizes, a series of switches, means for carrying the cut-off letter-strips to the switches, an electric type-writing mechanism, and circuits from the switches to the electric devices for operating the type-bars, substantially as described.

11. In a printing-telegraph, the combination with a transmitter, of a letter-strip cutter constructed to cut off strips of varying sizes, a multiple switchboard means for carrying the cut-off letter-strips varying distances along the switchboard, an electric type-writing mechanism, and circuits from the switches of the multiple switchboard to the magnets for operating the type-bars of said type-writing mechanism, substantially as described.

12. In a printing-telegraph, the combination with a transmitter, of a letter-strip cutter constructed to cut off strips of varying sizes, a multiple switchboard having a series of rising and falling switches, means for carrying the cut-off letter-strips over and through the switches, an electric type-writing mechanism, and circuits from said switches to the magnets of said type-writing mechanism, substantially as described.

13. In a printing-telegraph, the combination with a transmitter, of a letter-strip cutter constructed to cut off strips of varying sizes, a multiple switchboard, means for carrying the cut-off letter-strips to the switches, type-bars operated by magnets, circuits from the switches to the magnets of said type-bars, and a circuit for operating a spacing device be-

tween different words printed by the type-bars, substantially as described.

14. In a printing-telegraph, the combination with a transmitter, of a letter-strip cutter 70 constructed to cut off strips of varying sizes, a multiple switchboard, means for carrying the cut-off letter-strips to the switches of said board, an electromagnetically-operated type-writer, circuits from said switches to the 75 type-bar magnets of said type-writer, a circuit and mechanism for operating a spacing device, and mechanism for changing the position of the paper to print a new line, substantially as described.

80 15. In a printing-telegraph, the combination with a transmitter, of a letter-strip cutter constructed to cut off strips of varying sizes, a multiple switchboard, means for carrying the cut-off letter-strips to the switches of said board, an electromagnetically-operated type-writer, circuits from the switches to the magnets of said type-writer, a circuit and mechanism for operating the spacing device between the words printed by said type-writer, 85 and means for moving the paper-cylinder for capitalization, substantially as described.

90 16. In a printing-telegraph, the combination with a transmitter, of a letter-strip cutter constructed to cut off strips of varying sizes, 95 a multiple switchboard, means for carrying the cut-off letter-strips to the switches of said board, an electromagnetically-operated type-writer, circuits from the switches to the magnets of said type-writer, means for operating 100 a spacing device, a circuit and means for moving the paper-cylinder for capitalization, and a locking device for holding said paper-cylinder in the capitalizing position, substantially as described.

105 17. In a printing-telegraph, the combination with a transmitter, of a letter-strip cutter constructed to cut off strips of varying sizes, a multiple switchboard, means for carrying the cut-off letter-strips to the switches of said board, an electromagnetically-operated type-writer, circuits from the switches to the magnets of the type-writer, means for operating 110 a spacing device, a circuit and means for moving the paper-cylinder laterally, a locking device therefor, and a circuit and means for unlocking the same, substantially as described.

115 18. In a printing-telegraph, the combination with a transmitter, of a letter-strip cutter 120 constructed to cut off strips of varying sizes, a multiple switchboard, a letter-strip carrier, an electric type-writer, circuits from the switches of said board to the type-writer, a circuit and means for operating a spacing device, and circuits and means for rotating the paper-cylinder and moving the same laterally and longitudinally, substantially as described.

125 19. In a telegraphic apparatus, the combination of a feeding device, an electrically-operated cutter for cutting off letter-strips, an

electric circuit for controlling the motion of these devices and means for feeding a perforated strip between contacts in said circuit, for making and breaking the same, substantially as described.

20. In a telegraphic apparatus, the combination of a feeding device, an electrically-operated cutter for cutting off letter-strips, an electric circuit for controlling the motion of these devices, an electrically-operated stop-motion for the feeder, and means for feeding a perforated slip between the contacts in said circuit, for governing the motions of said cutter and stop-motion, substantially as described.

21. In a telegraphic apparatus, the combination of a feeding device, an electrically-operated cutter for cutting off letter-strips, an electric circuit for controlling the motion of these devices, an electrically-operated holder for the letter-strip, and means for feeding a perforated strip between contacts in said circuit, for controlling the motion of the cutter and holder, substantially as described.

22. In a telegraphic apparatus, the combination of a feeding device, an electrically-operated cutter for cutting off letter-strips, an electric circuit for controlling the motion of these devices, an electrically-operated pusher, and means for feeding a perforated strip between the contacts in said circuit for governing the motions of the cutter and pusher, substantially as described.

23. In a telegraphic apparatus, the combination of a feeder, a stopping device therefor, a cutter for cutting off letter-strips, a holder to temporarily keep the same, a pusher to force each letter-strip out of the way of the succeeding strip, magnets for operating said cutter, holder and pusher, a circuit for controlling said magnets, and means for feeding a perforated strip through contacts in said circuit for controlling said feeder, cutter and pusher, substantially as described.

24. In a telegraphic apparatus, the combination of a feeder, a stopping device for the same, a cutter to sever the letter-strips, a holder to temporarily keep the same, a carrying device, a pusher for transferring the

letter-strips to the carrying device, an electric circuit for controlling the motions of these devices, and means for feeding a perforated strip between contacts in said circuit, substantially as described.

25. In a device of the character described, the combination of a feeder, a cutter, mechanism for automatically varying the intervals between the cuts thereof, a switchboard, means for carrying the letter-strips severed by the cutter under the switches of said switchboard, and an electric apparatus operated by said switches, substantially as described.

26. In a device of the character described, the combination of a feeder, a cutter, mechanism for automatically varying the intervals between the cuts thereof, a switchboard,

and means for carrying the severed letter-strips under the switches of said switchboard, an electrical type-writer, and electrical connections between the switches and the type-writer, substantially as described.

27. In a device of the character described, the combination of a feeder, a cutter, mechanism for automatically varying the intervals between the cuts thereof, a holder for the letter-strips cut off by the cutter, a pusher for the same, a switchboard, a carrier arranged to force said letter-strips under switches on the switchboard, an electrical type-writer, and electrical connections between the type-writer and the switches, substantially as described.

28. In a device of the character described, the combination of a feeder, a stop for the same, means for operating said stop, a cutter, mechanism for automatically varying the intervals between the cuts thereof, a holder for the strips cut from a strip carried in by the feeder, a pusher for the same, a switchboard, a carrier arranged to force said severed letter-strips under switches on the switchboard, an electrical type-writer, and electrical connections between the switches and the type-writer, substantially as described.

29. In a device of the character described, the combination of a switchboard having a series of switches thereon, each switch being shorter than the next preceding and provided with a contact-point, a letter-strip cutter, a carrier constructed to carry severed letter-strips made by the cutter under said switches to move the contact-points, an electrical instrument, and electrical circuits between said instrument and the contact-points of the switches, substantially as described.

30. In a device of the character described, the combination of a switchboard having a series of switches with lips at gradually-decreasing distances from one edge of the switchboard, a cutter for cutting off a series of independent letter-strips, a carrier for carrying said letter-strips under the switches and a guiding-bar near said switchboard having a groove therein to receive the bent end of the letter-strips, substantially as described.

31. In a device of the character described, the combination of a feeder, a motor therefor, a brake for stopping said motor, a cutter, a magnet and electrical circuit for operating said cutter, a pusher, a magnet and electrical circuit for operating said pusher, and contact-points connected with the brake for completing said circuits, substantially as described.

32. In a device of the character described, the combination of a feeder, a cutter, a letter-strip holder, an operating device comprising an electromagnet, a lever 31 carrying the holder 28 and the armature 30, and a weight 130 operating in opposition to said magnet, substantially as described.

33. In a device of the character described, of a letter-strip pusher comprising an electro-

magnet a lever 31, an armature 30 and a pawl 45 carried by said lever 31, a lever 48 for moving the pusher and having projections on its sides, and a rod 49 mounted on said lever 48, and carrying the pusher, substantially as described.

34. In an electrical type-writing apparatus, the combination of the type-bars, the operating means for the same and the frame thereof, 10 with a magnet and intermediate connections with the cylinder for partially rotating the same between the printing of two letters, and a magnet and intermediate connection with the cylinder for controlling the endwise motion of the same, substantially as described.

35. In an electrical type-writing apparatus, the combination of the type-bars, their operating means and the frame thereof, with a shaft, a block fixed on said shaft having a 20 groove therein, a paper-cylinder loosely fitting said block and having a flange running in said groove, a shaft carrying said block, and means for causing said cylinder to intermittently rotate between the printing of the letters and to move endwise between the printing of the lines, substantially as described.

36. In a type-writer, the combination with a paper-cylinder, having an internal rack formed on said cylinder, of an escapement operating on said rack, means for operating said escapement, and a spring for moving the cylinder as the escapement operates, substantially as described.

37. In an electrical type-writing apparatus, 35 the combination with a paper-cylinder having an internal rack formed on said cylinder, an escapement operating on said rack, a magnet for operating said escapement in one direction, and a spring acting in opposition thereto, 40 substantially as described.

38. In a type-writer and in combination with the type thereof, a rotatable shaft, a support for the paper-cylinder fixedly attached to and rotating with said shaft, a paper-cylinder 45 traveling longitudinally along and over said support and arranged to support the paper under the pressure of the type, and means for moving said cylinder longitudinally set in said block, substantially as described.

39. In a type-writer and in combination with the type thereof, a rotatable shaft, a support for the paper-cylinder fixedly attached to and rotating with said shaft, a paper-cylinder, traveling longitudinally along and over 55 said support, and arranged to support the paper under the pressure of the type, and mechanism for regulating the movement of the cylinder over said support inclosed in said cylinder, substantially as described.

40. In a type-writer and in combination with the type thereof, a rotatable shaft, means

for intermittently rotating said shaft, a support for the paper-cylinder, fixedly attached to and rotating with said shaft, a paper-cylinder traveling longitudinally over said support, and arranged to support the paper under pressure of the type, and mechanism for regulating the longitudinal movement of the cylinder inclosed in said cylinder, substantially as described.

41. In a type-writer, a paper-cylinder, a rack on said cylinder, a support for the cylinder, a shaft carrying said support, an escapement acting on the rack, a magnet for operating the same, and an electric circuit 75 for the magnet passing through said shaft, substantially as described.

42. In an electric type-writer, in combination with the frame and paper-cylinder thereof, a pair of bearings for the shaft of the paper-cylinder, mounted on the frame, magnets acting on said bearings, and springs acting in opposition to said magnets, substantially as described.

43. In an electric type-writer, in combination with the frame and paper-cylinder thereof, a pair of bearings for the shaft of the paper-cylinder mounted in recesses in the frame, magnets acting on said bearings, springs acting in opposition to said magnets, a locking 90 device for continuing the action of said magnets, and a releasing device for said lock, substantially as described.

44. A system of telegraphing comprising a transmitting mechanism constructed and arranged to transmit electrical impulses varying in length with each different letter, but always the same length for the same letter, a cutting mechanism whose operation is governed by the impulses so transmitted and a 100 type-writer operated at intervals corresponding with the impulses, substantially as described.

45. A system of telegraphing comprising a transmitter, constructed and arranged to 105 transmit electrical impulses varying in length with each different letter, but always the same length for the same letter, a cutting mechanism whose operation corresponds with the impulses so transmitted and a printing mechanism operating at intervals corresponding with the impulses of the transmitter and the operations of the cutting device, substantially as described.

In testimony whereof I affix my signature, 115 in the presence of two witnesses, this 12th day of November, 1897.

SYLVESTER J. SMALL.
